BOBBIN WITH TAIL-TIE GUDGEON

Lester F. Burlein, Honesdale, Pa., assignor to Cloverleaf Freeland Corporation, Honesdale and Hazleton, Pa., a corporation of Pennsylvania

Application February 28, 1950, Serial No. 146,719

16 Claims. (Cl. 242—125)

This invention relates to bobbins or spools but more particularly and specifically to a take-up bobbin and is a continuation in part of my earlier filed but now abandoned application Serial No. 54,655, entitled "Bobbins with Tail-Tie Gudgeon."

A take-up bobbin or spool is one about which yarn, or the like, is wound and the loaded bobbin or spool is then used as a yarn supply means for certain other textile mill operations as for instance warping operation. It is highly desirable and advantageous that the trailing end of the yarn on the bobbin be available for attachment to the leading end of the yarn on another bobbin so that when the bobbins are acting as yarn supply means an uninterrupted or what might be termed a "magazine feed" of yarn is provided. During the loading operation the barrel of the bobbin or spool is disposed in a horizontal plane and a horizontally disposed gudgeon or axle is provided as an axis for supporting the bobbin for rotation. Ordinarily in the use of the loaded bobbin where the yarn goes to the warp beam or the quill the bobbin is supported so that its barrel is in a vertical plane.

The basic object of the present invention is the provision of a take-up bobbin in which the gudgeon or axle performs the dual function of acting as a bearing for supporting the bobbin for rotation on a horizontally disposed axis and simultaneously serving as a tail-tie to which the trailing end of the yarn is secured or snubbed against unwinding during the loading operation and is quickly available for attachment to the leading end of yarn which is wrapped about another and separate bobbin.

A further object of the invention is the provision of a bobbin or spool having a novel combined gudgeon and tail-tie in which the tail-tie is of a construction whereby it can be easily, conveniently and comparatively cheaply provided.

A further object of the invention is the provision of a combined gudgeon and tail-tie which is adapted for use with bobbins or spools having either a hollow or a solid barrel.

Other objects, novel features of construction and advantages of the invention will appear from the following description when read in the light of the accompanying drawings and be understood by those familiar with the art.

The inventive concept can be embodied in constructions and arrangements differing specifically from one another and several bobbins or spools embodying the inventive concept are illustrated in the accompanying drawings wherein:

Fig. 1 is a view in side elevation of a bobbin embodying the invention in one of its forms.

Fig. 2 is an end view of the right-hand end of the bobbin of Fig. 1.

Fig. 3 is a longitudinal sectional view through the bobbin of Fig. 1.

Fig. 4 is a strung out view in side elevation of the two pieces making up the combined gudgeon and tail-tie.

Fig. 5 is a view in side elevation of the assembled gudgeon and tail-tie.

Fig. 6 is a longitudinal sectional view on the line 6—6 of Fig. 5.

Fig. 7 is a view in side elevation, parts thereof being broken away and shown in longitudinal section, of a bobbin embodying a modified form of the invention, the bobbin being of the solid barrel type.

2

Fig. 8 is an end view of the right-hand end of the bobbin of Fig. 7.

Fig. 9 is a longitudinal vertical sectional view through the combined gudgeon and tail-tie, a portion of the bobbin barrel and head also appearing in section.

Fig. 10 is a detailed fragmentary view of an end of a bobbin showing a still further modified form of tail-tie and gudgeon, a portion of the view being in vertical section.

Fig. 11 is a side view illustrative of the manner of support and drive of a take-up bobbin.

Fig. 12 is a top plan view of the arrangement appearing in Fig. 11.

Fig. 13 is a view in side elevation illustrating the manner in which the trailing and leading ends of yarn on loaded take-up bobbins are interconnected to provide continuous yarn feed for machines used in textile mill operations.

Having reference now to Figs. 1 to 6 of the drawings 20 wherein one form of the invention, not to be considered the preferred form because first described, is illustrated, A is a hollow open-ended tube constituting the barrel of the bobbin. This barrel is circular in cross sectional configuration and has at its ends heads B and C each of which is preferably, but not necessarily, provided with a circular groove 1 to telescopically receive a barrel end.

In addition to the main heads B and C the bobbin is provided with supplemental heads D which are identical of construction and one of which is in each end of the 30 barrel and abuts the inner face of the adjacent main bobbin head. These supplemental heads are preferably a single casting which has been machined and specifically to comprise a circular disc 2 of the proper diameter to snugly fit the barrel and on their inner faces are provided with a hub-like portion 3 from which extends a hollow externally threaded collar or shank 4. A hollow 35 interiorly threaded tube 5 extends longitudinally through the barrel and threadedly interconnects the shanks 4 of the two oppositely positioned supplemental bobbin heads D.

The hub-like portions as well as the supplemental heads are provided with a bore to provide a passageway 6 which is of the proper diameter to receive a pin, shaft or spindle upon which the bobbin can be mounted for 45 warping or quilling operations.

The gudgeon, designated as an entirety by E, is composed of two parts one of which is lettered F and the other G. The part F embodies a head 7 and a collar 8 provided with a passageway or bore 9. The part G is 50 of tubular form and has a diameter substantially the same as the diameter of the bore 9 of the part F. This element is provided with a longitudinal bore or passageway 10 and intermediate its length and exteriorly is provided with an outwardly extending circumferential flange 11 having one of its faces tapered as at 12. The 55 assembled gudgeon is illustrated in Fig. 5 from which it will be seen that the end 13 of the part G is telescopically received by the bore of the part F. The part G is retained in the part F by a pressed fit which is sufficiently tight to prevent longitudinal displacement of the parts in respect to one another and axial rotation of the parts in respect to one another. The part F is milled out as at 14 and the flange 11 of the part G is milled out as at 15 and when the two parts of the gudgeon are 60 fitted together these milled out parts are placed in alignment so as to provide a slot designated as an entirety by H.

The disc 2 of the supplemental head with which the gudgeon is associated is milled out to provide a recess 65 16 of the proper size and configuration to snugly receive the head 7 of the gudgeon part F while the collar of this part extends through a suitable opening 17 cen-

trally provided in the head C. Upon associating part G of the gudgeon with the part F it will be seen that the tapered or inclined face 12 of the flange 11 makes an acute angle with the end or shoulder 18 of the collar 8. This provides a space for the reception of yarn and will retain the yarn against displacement because of the ease with which the yarn can be wedged between the tapered face and shoulder.

Each of the bobbin heads is suitably secured to its respective end of the barrel by a plurality of screws 19 which pass through the heads and have threaded engagement with the disc portions 2 of the supplemental head D. The bobbin head C at its edge is provided with a slot 20 which is substantially V-shaped and has its bottom or inner end 21 terminating at substantially the point where said slot meets the outer face of the bobbin barrel A.

In addition to the foregoing there is associated with the bobbin head C a plurality of elements which I have termed grooved buttons K. These buttons are arranged circumferentially around the gudgeon E in spaced relationship to one another and to the gudgeon and specifically comprise a threaded shank 22 which passes through the bobbin head for threaded engagement with the disc portion 2 of the supplemental head. At their outer ends and above the bobbin head C each of these buttons is grooved as at 23.

The bobbin at its end opposite to that which is provided with the gudgeon carries or is provided with only that portion or part of the gudgeon F. The collar portion 8' thereof provides an axle for rotatably supporting the bobbin.

The two-part gudgeon E by reason of its outwardly extending collar 8 provides the dual function of an axle for rotatably supporting one end of the bobbin and acting as a tail-tie for the end of a piece of yarn which is to be wrapped on or about the bobbin barrel.

In use the two bobbin collars are rotatably supported in horizontally disposed bearings to support the bobbin for rotation about a horizontal axis and the end of a piece of yarn to be wrapped on or about the bobbin barrel is wrapped around the gudgeon in the V-shaped passageway or groove lying between the shoulder 18 of the gudgeon part F and tapered face of the flange of the gudgeon part G. The yarn is then carried around the grooved buttons K for several turns with the yarn lying in the grooves 23 of the buttons. From a button adjacent the head groove 20 the yarn is carried to and through the groove and a turn or two is taken about the bobbin barrel. The bobbin is now ready for operation and the end of the yarn is held against the possibility of unwinding thus assuring a proper winding operation on the bobbin barrel.

At the end of an operation and when the yarn end is to be released from the gudgeon it is often found that it is wedged very tightly and will not easily or readily release. In this event a knife or other suitable object is inserted into the slot H to facilitate cleaning out any yarn which is trapped or tightly wedged in the groove of the gudgeon.

From the foregoing it will be seen that the bobbin can be assembled and taken apart quickly and easily. The main heads are secured to the supplemental heads by the screws 19 and are also secured to this element by the grooved buttons K. The main heads can be easily and quickly associated with a supplemental head or detached therefrom. The supplemental heads have threaded engagement with the tube 5. Rotation of the supplemental heads in respect to the tube 5 will pull them and the main heads they carry toward one another until the ends of the barrel are seated tightly in the grooves 1 in the inner faces of the main heads.

The arrangement provides a convenient, simple, yet highly efficient means for securing or snubbing the end

of a yarn against slippage so as to assure proper winding operation.

The manner of supporting and driving the bobbin during the winding operation is illustrated in Figs. 11 and 12. The gudgeons at the opposite ends of the bobbin are rotatably supported in the bearing portions 25 in the ends of the fingers or arms 26. These arms in turn are suitably pivotally mounted as at 27 so that the bobbin, while being rotated in the manner hereinafter to be explained, can swing in a vertical plane. A roll M is associated with each bobbin. These rolls are suitably slowly rotated by a power means, not shown, to rotate about their horizontally disposed axles 28. These rolls are fixed and at the start of the winding operation the roll, see Fig. 12, engages the barrel A of the bobbin but as the winding operation continues and the barrel of the bobbin is filled with yarn the bobbin is caused to move away from the roll which movement is accommodated by the described pivotal mounting of the bearing supporting fingers 26.

By reference to Fig. 12 it will be seen that at that end of the bobbin provided with a combination gudgeon and tail-tie the bearing 25 is disposed outwardly beyond the tail-tie making it possible to securely snub the end of the yarn in the tail-tie and to wrap the yarn about the buttons K in the manner hereinbefore described.

Although all installations and arrangements may not be identical to that illustrated in Figs. 11 and 12 in all instances the means for supporting the bobbin for rotation about a horizontally disposed axis is such that the tail-tie is accessible to permit the yarn to be secured therein.

The manner of operation, previously described, following the completion of the loading of a bobbin when the yarn thereon is being used for warping or quilling is illustrated in Fig. 13 of the drawings. For convenience and clarity of description the two loaded bobbins are designated as an entirety by N and O. Each of them has its barrel extending in a vertical plane and is held against displacement by a vertical pin or spindle 30 and it is to be noted that their ends provided with the combination gudgeon and tail-tie E are at the lower ends of the bobbins. The leading end 31 of the yarn on the bobbin N goes to the warping or quilling machine while the trailing end 32 of the yarn on this bobbin has been released from the tail-tie and the buttons and is tied as at 33 to the leading end 34 of the yarn wound about or loaded on the bobbin O. The trailing end of the yarn on the bobbin O is still secured in the tail-tie and about the buttons of this bobbin and is ready to be released for securing to the leading end of the yarn on still another bobbin so that a continuous feed of yarn can be maintained or provided.

Departures from the specific tail-tie structure illustrated in Figs. 1 to 6 of the drawings can be made and an illustration of a modified form of the invention is illustrated in Figs. 7 to 9 inclusive of the drawings.

The construction appearing in the figures of the drawings is particularly adapted for a bobbin having a solid wooden barrel such as the barrel P provided with a central longitudinal bore 36 for the reception of a pin or pindle when the bobbin is being used for warping or quilling. The barrel is provided with metallic, preferably die cast, heads. The head Q at the barrel end 37 is centrally provided with an opening 38 in which is press fitted the outwardly extending gudgeon R provided at its inner end with a head 39 which abuts the inner face of the bobbin head Q. This gudgeon has a longitudinal bore 40 in alignment with and forming a continuation of the barrel bore 36.

The bobbin head S at the opposite end 41 of the barrel is provided centrally with an internally and externally collared opening to provide a hollow socket 42 having an outer end 43 disposed in a plane beyond the outer face of the head. The heads can be secured to the barrel in accordance with conventional practice as for instance a plurality of rivets 44.

The head S, like the previously described head C of the other form of bobbin, is provided with a slot 45 which extends inwardly from the peripheral edge 46 of the head a sufficient distance to position its inner end 47 in substantial alignment with the outer face 48 of the barrel. In place of the described channelled buttons K this head is provided with a circular retaining ring T the outer face of which is channelled as at 49 while its inner face is in the form of a fillet to provide a finger or thumb groove. This inner groove, acting as a guide for the fingers or thumb of an operator assists the operator in guiding the yarn end into and around the groove or channelway 49. It also assists the operator in picking up any end of yarn which may still remain wrapped around the gudgeon after the bobbin is empty. Although this retainer is referred to as a ring it does not constitute a closed ring in that its ends 50 and 51 are at spaced relationship to leave an opening 52 positioned opposite the inner end 47 of the head slot 45.

The end 41 of the bobbin is provided with a gudgeon V which in combination with the head socket 42 provides a combined gudgeon and tail-tie. This gudgeon is an elongated hollow tubular member the inner end 53 of which has a pressed fit with the socket 42 so that the bore 54 of the gudgeon is in alignment with and forms a continuation of the bore 36 of the barrel. The outer end 55 of the gudgeon V and the gudgeon R in reality form axles which are rotatable in suitable bearings which support the bobbin for rotation about a horizontally disposed axis.

Intermediate its length the gudgeon V is provided with an outwardly extending circumferential flange 56 having an inner tapered face 57 in opposed separated relationship to the outer end 43 of the head socket 42. This construction provides a V-shaped groove 58 for the reception of an end of yarn being wound about the bobbin. A yarn strand inserted into this groove will be wedged between the outer end of the head socket and the inner face of the gudgeon flange and be thereby retained against accidental displacement. The outer end 43 of the head socket is milled out as at 59 while the gudgeon flange is milled out as at 60 to provide a slot 61. On occasion, at the termination of a winding operation the yarn end to be released from the gudgeon is wedged very tightly and cannot be easily or readily released. A knife or other suitable object can be inserted into the slot 61 of the tail-tie to facilitate releasing or cleaning out any yarn which has become very tightly wedged in the groove.

The operation of this construction is similar to that previously described and comprises bringing the yarn end from the barrel through the head slot 45 and carrying it to and wrapping it about the groove in the tail-tie gudgeon so that it is snubbed or wedged in the bottom of the groove 58 and then carrying the yarn about the groove of the retaining ring T.

A further modification of the invention which provides a combined tail-tie and gudgeon appears in Fig. 10 of the drawings wherein the bobbin head is fragmentarily illustrated at W and has formed integrally therewith a socket X provided with a bore 63. The socket has an outwardly extending end 64 and the elongated tubular gudgeon Y has a pressed fit in the socket. The outer end 65 of the gudgeon provides an axle upon which the bobbin is rotatably supported. The gudgeon is provided with a central longitudinal bore 66 and intermediate its length is externally provided with a circumferential groove 67 in which a split ring 68 is retained. The yarn end receiving and snubbing space 69 is between the inner face of this ring and the outer slightly rounded or tapered end face 70 of the head socket end 64. The space between the ends 71 and 72 of the ring will serve the same purpose as the previously described slots H and 61 in the other forms of the invention, namely, to permit the use of a suitable tool for releasing yarn which is wedged in and will not easily release from the yarn snubbing opening or groove.

Although it is not essential it is desirable in the practice of the invention to make the gudgeons of stainless steel.

The inventive concept can be embodied in structures differing specifically from those illustrated without departing from the inventive concept and the invention is accordingly to be limited only by the scope of the following claims.

What I claim is:

1. In a take-up bobbin or the like embodying a barrel 10 having heads at its ends and adapted to be mounted for rotation and to have a length of yarn wound about its barrel, a gudgeon mounted in the bobbin at and extending outwardly beyond one of said bobbin heads and serving as an axle adapted to be rotatably supported on a 15 bearing with the bobbin barrel disposed in a horizontal plane, the gudgeon being provided with a longitudinal bore adapted to receive a vertically extending spindle for holding the bobbin with its barrel disposed in a vertical plane, said gudgeon being provided with a circumferential groove 20 adapted to receive and hold against movement an end of the length of yarn, a plurality of outwardly extending elements at the outer face of said bobbin head and arranged in spaced aligned relationship circumferentially of the head at a point between the gudgeon and the outer peripheral edge of the head, each of said elements being provided with a groove adapted to receive the yarn, said head being provided with a slot extending from its peripheral edge inwardly and having its inner end substantially in alignment with the outer face of the barrel, and 25 the yarn adapted to extend from its point of securement to the gudgeon about said elements and through said head slot and about the bobbin barrel.
2. A construction as defined in claim 1 wherein, the gudgeons extend outwardly beyond the bobbin heads to 30 provide elements upon which the bobbins can be supported for rotation about a horizontal axis.
3. In a take-up bobbin or the like embodying a barrel having heads at its ends and adapted to be mounted for rotation and to have a length of yarn wound about its 40 barrel, a two-part gudgeon associated with one of said bobbin heads, one of said gudgeon parts being an outer part and having a head beneath the barrel head and a tubular portion extending outwardly through the barrel head, said part being provided with a longitudinal bore, the other part of said gudgeon being the inner part and 45 being of tubular form and having an inner end telescopically received by the bore of the outer gudgeon part, said inner gudgeon part being provided with a longitudinal bore adapted to receive a pintle for holding the bobbin with its barrel disposed in a vertical plane, the 50 outer end of the outer gudgeon part being square to provide a shoulder, the inner gudgeon part being provided with a circumferential flange having one of its sides bevelled to provide an inclined wall, the inclined wall of said flange being in abutment with said shoulder to provide 55 a circumferential groove which is substantially V-shaped in cross sectional configuration, and said groove adapted to receive and hold against movement the end of a length of yarn which is to be wound about the bobbin barrel.
- 60 4. A construction as defined in claim 3 wherein, the outer end of the outer gudgeon part is provided with a cut-out portion and the flange of the inner gudgeon part is provided with a cut-out portion, said cut-out portions being in alignment to provide a slot extending across the 65 V-shaped groove and adapted to receive an implement for engaging and freeing yarn trapped in said groove.
5. A construction as defined in claim 3 wherein, a plurality of button elements are carried by the outer face of said bobbin head and disposed circumferentially there- 70 of in spaced relation at a point between the gudgeon and the outer peripheral edge of the bobbin head, each of said buttons being provided with a groove adapted to receive yarn, and the bobbin head being provided with a slot ex- 75 tending from its peripheral edge inwardly and terminat- ing substantially in alignment with the outer face of the

bobbin barrel to provide a passageway for yarn extending from one of said buttons to and about the bobbin barrel.

6. For use with a take-up bobbin or the like which is adapted to be rotatably mounted to have a length of yarn wound about its barrel, a combined bearing and yarn tail-tie in the form of a two-part gudgeon, said gudgeon parts being of tubular form with one gudgeon part telescopically receiving the other gudgeon part, said parts having a pressed fit to hold them against movement in respect to one another, the inner gudgeon part being provided with a longitudinal bore adapted to act as a bearing for supporting the bobbin for rotation, the outer gudgeon part terminating in a shoulder, the inner gudgeon part being provided intermediate its length with a circumferential flange disposed adjacent said shoulder, and said shoulder and flange forming a circumferential groove having a narrow bottom adapted to receive and hold the end of a length of yarn against movement.

7. A construction as defined in claim 6 wherein, the 20 gudgeon parts are cut-out to provide a slot extending transverse the groove formed by the shoulder and flange of the gudgeon parts.

8. For use with a take-up bobbin or the like which is adapted to be rotatably mounted to have a length of yarn wound about its barrel, a combined bearing and yarn tail-tie in the form of a two-part gudgeon, said gudgeon including inner and outer parts, the inner part being telescopically carried by the outer part and having a pressed fit therewith to prevent movement of said parts in respect to one another, the outer gudgeon part being provided with a head adapted to be disposed beneath the head of a bobbin and an elongated tubular collar adapted to extend through and beyond the bobbin head and its outer end forming a shoulder, the inner gudgeon part being provided with a longitudinal bore adapted to receive a pintle for holding the bobbin with its barrel disposed in a vertical plane and being provided exteriorly with a circumferential flange having a tapered side wall the bottom of which is in abutment with said collar shoulder, and said arrangement providing between the shoulder and the flange a circumferential groove adapted to engage and hold the end of a length of yarn against movement.

9. In a take-up bobbin or the like, a barrel and a head therefor, said head being centrally provided with an integrally formed open-ended socket having beyond the outer face of the head a surrounding collar, a gudgeon having an end in the socket and an exterior end extending outwardly beyond the outer face of the barrel head, the outwardly extending end of the gudgeon being provided with a circumferential flange spaced inwardly from its outer most end and positioned adjacent the outer end face of the socket collar, and that wall of the flange opposed to the socket collar end face being bevelled to provide in combination with said end face a V-shaped groove encircling the gudgeon.

10. In a take-up bobbin or the like, a barrel, a head for the barrel provided centrally with an open-ended socket having beyond the exterior face of the head a surrounding collar, a gudgeon having an inner end disposed and retained in said socket and an outer end extending outwardly beyond the outer end of the socket collar, the outer end of the gudgeon being exteriorly provided with a circumferential channelway, a split ring in said channelway and said ring being positioned to have its inner face closely adjacent the outer end of the socket collar to provide a groove adapted to receive a length of yarn.

11. A construction as defined in claim 10 wherein, the outer end of the socket collar is rounded to provide a groove of progressively reduced width towards its bottom.

12. In a take-up bobbin, or the like, a barrel having heads at its ends and adapted to be mounted for rotation to have a length of yarn wound about its barrel, a gudgeon extending outwardly from one barrel head, a

plurality of button elements at the outer face of said bobbin head and arranged in spaced aligned relationship circumferentially on the head at a point between the gudgeon and the outer peripheral edge of the head, each of said buttons being provided with a groove adapted to receive the yarn, said head being provided with a slot extending from its peripheral edge inwardly and having its inner end substantially in alignment with the outer face of the barrel, and the yarn adapted to extend from its point of securement to the gudgeon about said button elements and through said head slot and about the bobbin barrel.

13. A construction as defined in claim 12, wherein a gudgeon extends outwardly at each end of the bobbin to provide a rotative support element for the bobbin, that gudgeon associated with the slotted head being provided with means for engaging and securing to the gudgeon the yarn prior to the engagement of the yarn with the grooved button elements.

14. In a take-up bobbin or spool embodying a barrel adapted to have wound about it a length of yarn with the leading end of the yarn free of and extending outwardly from the barrel, a head of a diameter substantially greater than the barrel at each of the barrel ends, a gudgeon at each end of the barrel extending outwardly to a point beyond its associated barrel head, the extending ends of said gudgeons adapted to be disposed in a bearing for supporting the bobbin for rotation about a horizontal axis, one of the bobbin heads being provided with a slot extending from its peripheral edge inwardly to a point substantially in line with the outer peripheral face of the bobbin barrel to provide a passageway for the free leading end of the yarn to the outer face of the barrel head, the outwardly extending end of the gudgeon associated with said slotted barrel head being provided with means for engaging and securing to the gudgeon the free leading end of the yarn to prevent slippage of the yarn in respect to the bobbin, and the slotted barrel head on its outer face being provided with outwardly extending grooved means about which the free leading end of the yarn may be wrapped after its securement to the gudgeon.

15. In a take-up bobbin or the like, a barrel, a head for the barrel provided with an outwardly extending open-ended socket, a gudgeon having an inner-end disposed and retained in the socket, the other end of the gudgeon extending outwardly to a point beyond the outer face of the barrel head, the outwardly extending gudgeon end being exteriorly provided with a circumferential channelway, a resilient split ring encircling the gudgeon and being seated under resilient tension in the gudgeon channelway, and the ring and the outer end of the head socket forming between them a groove adapted to receive and frictionally hold a length of yarn.

16. A construction as defined in claim 15 wherein, the outer end of the socket is rounded to provide a groove of progressively reduced width towards its bottom.
